UNITED STATES PATENT OFFICE

EDMOND P. BIXER, OF NEW YORK, N. Y.

CURTAIN HEADING

Application filed December 1, 1932. Serial No. 645,295.

This invention relates to draperies, and particularly to an improved curtain heading, the object being to provide an improved construction wherein the curtain may be properly supported and at the same time present uniform, evenly-spaced folds or gatherings.

Another object of the invention is to provide a curtain heading wherein a plurality of passageways are provided for the rod, tape or other support, the passageways being arranged to either support the curtain in a flat position or in a gathered position.

An additional object is to provide a curtain heading wherein the upper part of the curtain is turned over and stitched in place, together with a tape formed with spaced openings through which a rod or other support is adapted to pass when the heading is to be gathered.

A still further object, more specifically, is to provide a heading for curtains wherein the curtain is turned over at the upper end and formed with a short hem or with one or more loops in association with a rod receiving tape formed of ordinary closely woven fabric or of a braided strip.

In the accompanying drawings—

Figure 1 is an elevation of a heading for curtains disclosing an embodiment of the invention, the same being shown in connection with a supporting rod;

Figure 2 is a sectional view through Figure 1, approximately on the line 2—2, the same illustrating how the supporting rod is threaded through the supporting tape on the rear of the curtain body;

Figure 3 is a view similar to Figure 2 but showing how loops or gatherings are formed at spaced intervals when the curtain has been moved longitudinally of the supporting rod a certain distance;

Figure 4 is an enlarged fragmentary elevation showing part of the curtain heading illustrated in Figure 1;

Figure 5 is a sectional view through Figure 4 on the line 5—5;

Figure 6 is a view similar to Figure 5 but showing a tightly woven piece of fabric acting as a piece of tape instead of the braid shown in Figure 4;

Figure 7 is a view similar to Figure 5 but showing a modified construction wherein only one loop of the curtain body is provided;

Figure 8 is a modified form to that shown in Figures 5 and 7, the structure illustrating 55 a hem on the upper end of the curtain body with a supporting tape associated therewith.

Referring to the accompanying drawings by numerals, 1 indicates a curtain of any desired kind the same being supported on a 60 rod 2 of any desired kind. It will be evident that cords or other supports may be provided instead of the stiff rod 2, if desired. As illustrated in Figures 1, 4 and 5 the curtain body 1 is turned over at 3 (Figure 5) and 65 is stitched at 4 and 5 whereby two supporting loops are presented having passageways 6 and 7. A tape 8 is held in place by stitchings 4 and 5 so that there is presented a third loop 9 through which the rod 2 may extend. 70 It will be understood that the tape 8 is on the reverse side of the curtain so that it will not be seen from the room. As illustrated in Figures 1 and 4, the tape 8 is braid while the structure illustrated in Figure 6 shows a tape 75 8' formed as ordinary fabric provided with a number of spaced apertures 10. These apertures have their edges bound in any suitable way as, for instance, a buttonhole stitch. In the braid shown in Figure 8 at the various 80 points 11 some of the yarns are omitted, thus providing long sections 12 and short sections 13.

When the rod 2 is threaded into the position shown in Figure 1 the curtain will hang substantially flat as illustrated in Figure 2. However, if it is desired to have gatherings in the curtain the same may be brought to the position shown in Figure 3, wherein suitable gatherings or loops 14 are presented. 85 These are equally spaced apart and are caused by the fact that the respective ends 15 and 16 are brought together, thus causing the portion 17 between these ends to bulge outwardly and be automatically spaced equal distances 90 apart, thus causing the curtain to hang in a very pleasing manner. Where the rod 2 is fitted into passageways 6 and 7 great care must be taken in producing these loops as 95 there is nothing to guide the hand when form- 100

ing the loops or gatherings. It will be readily understood that the supporting rod 2 can be arranged in the passageways 6 or 7 or 9 as preferred. Also, if the curtain is to remain flat, usually the rod 2 is passed beneath all of the sections 12 and 13 instead of being arranged as shown in Figures 1 and 2.

- As shown in Figure 7 the passageway 18 is provided formed by a single fold 19, and 10 the tape 8 is arranged completely below the fold 9. In Figure 8 there is only a slight hem 20 and the tape 8 is arranged completely below this hem except that part which is held in place by the stitching 21. In all of these 15 forms, as well as in the preferred form, the braid or tape 8 is arranged at the rear of the curtain body and as the braid is very flexible the curtain body may be gathered or left straight as desired.
- 20 The division of the sections 12 and 13, as shown in Figures 1 and 4, permits of quick gathering of the curtain with uniform tucks or gatherings. The same is true of the structure shown in Figure 6.

- 25 When the curtain body 1 is of lace or other light material, a double fold, as shown in Figure 5, is desirable as the curtain head is then substantially hidden and yet the curtain is supported in a very pleasing manner. The 30 portion forming the passageway 6 will readily gathered along the remaining part of the curtain so that there will not be a stiff and rigid appearance given to the upper edge of the curtain.

35 I claim:

1. A curtain heading comprising a looped formation at the upper end of the curtain presenting a pair of aligned passageways, a tape superposed on one of said passageways 40 presenting a third passageway, and a line of stitching at each edge of said tape extending through the tape, the curtain body and said looped formation.

2. A curtain heading including a supporting rod receiving tape positioned longitudinally at the rear of the curtain near the upper end, said tape being spaced from the upper edge and provided with spaced apertures, said apertures being arranged in 50 groups with a greater distance between certain apertures than others whereby the curtain may be folded to produce evenly spaced gatherings.

3. A curtain heading comprising a folded over portion at the upper end of the curtain, a tape arranged at the rear of the upper part of the curtain, a line of stitching extending through each edge of said tape and through the folded over portion, said tape 60 being adapted to receive a supporting member, said tape being formed with spaced openings whereby said supporting member may be arranged wholly interiorly of the tape, or arranged to extend through the various openings in a zig-zag path.

4. A heading for curtains comprising a fold, at the upper end of the curtain presenting a pair of spaced passageways for the reception of a supporting rod, and a tape forming a braiding over one of said passageways and presenting a third passageway, said tape being flexible throughout and provided with spaced openings through which said rod may be passed.

5. A curtain heading comprising in combination the upper end of a curtain, a flexible braid arranged at the back of the upper end of the curtain, a line of stitching at each edge of the braid for permanently connecting the braid to the curtain, said braid being formed with spaced groups of openings having substantially parallel yarns filling the space between the openings, and a closed formation braided structure at each edge for receiving said lines of stitching.
